UNITED STATES PATENT OFFICE.

PATRICK FLEMING AND JOSEPH LYON, OF DAYTON, OHIO, ASSIGNEES TO
JOHN A. BETSNER AND IRA C. KOEHNE, OF SAME PLACE.

DESIGN FOR A GAME-BOARD.

SPECIFICATION forming part of Design No. 31,104, dated June 27, 1899.

Application filed May 27, 1899. Serial No. 718,585. Term of patent 7 years.

To all whom it may concern:

Be it known that we, PATRICK FLEMING and JOSEPH LYON, of Dayton, county of Montgomery, and State of Ohio, have invented a certain new and original Design for a Game-Board; and we do hereby declare that the following is a full, clear, and exact description thereof, reference being had to the accompanying drawings, in which like letters refer to like parts.

In the drawings, Figure 1 represents a top plan view of a game-board embodying our design; and Fig. 2 is a sectional side elevation view thereof on line X X of Fig. 1, these two views being deemed necessary to fully illustrate our design.

The leading or essential feature of our design for a game-board consists of a substantially rectangular game-board having flanges projecting above its edges, the top surface of said game-board, near one end thereof, being divided by a series of lines into a series of spaces.

In the drawings, A indicates the game-board, and B the flanges projecting above the edges thereof.

C indicates the projection rising from near one end of the top surface of the game-board A and near the center of its width. D represents the series of lines which divide the top surface of said game-board adjacent said projection C into a series of spaces, and E represents a line extending across and near the opposite end of said game-board.

In the inner edge of the flange B, at the short end of the game-board nearest the projection C, is formed a recess F, extending substantially the width of the game-board.

What we claim is—

The design for a game-board, substantially as shown and described.

In witness whereof we have hereunto set our hands this 9th day of May, A. D. 1899.

PATRICK FLEMING.
JOSEPH LYON.
